CLAIM

I claim the ornamental design for a light weight hair piece, as shown and described.

DESCRIPTION

FIG. 1 is a right side view of a light weight hair piece showing my new design;

FIG. 2 is a right side view of a second embodiment of my design, wherein the modification resides in the black color of the band. The color, which is indicated by partial cross hatching for ease of illustration, is understood to extend throughout the entire surface of the band; and,

FIG. 3 is a perspective view of the design.
